UNITED STATES PATENT OFFICE.

JOSEPH T. WILLARD, OF O'FALLON, ILLINOIS, ASSIGNOR TO EUREKA STEEL RANGE COMPANY, OF O'FALLON, ILLINOIS, A CORPORATION OF ILLINOIS.

FURNACE GRATE.

Application filed March 16, 1923. Serial No. 625,561.

This invention relates to an improvement in grates for furnaces and the like and has for its primary object the purpose of providing a grate with improved shifting or 5 shifting means.

Another object of the invention is in providing a grate in which the parts thereof co-operate with one another in an improved manner for facilitating the assembly of the 10 grate.

A further object of the invention is in providing an improved support for the shifting or shaking member of the grate.

A still further object of the invention is in providing a grate with a pair of improved jaws for engaging and breaking clinkers which are too large for falling through the grate.

Another still further object of the invention is in providing a grate with closable discharge openings and means co-operating therewith for assisting the discharge of ashes through the openings.

Other and further objects will appear in 25 the specification and be specifically pointed out in the appended claims, reference being had to the accompanying drawings, exemplifying the invention, and in which:—

Figure 1 is a plan view of this improved 30 grate.

Figure 2 is a side elevation of Fig. 1.

Figure 3 is a plan view of the grate spider or shaking portion.

Figure 4 is a transverse section taken ap- 35 proximately on the line IV—IV of Fig. 1.

Referring by numerals to the accompanying drawings, 1 designates a grate-rest which is secured above the ash pit of a furnace in a well known manner by the annular 40 supporting base 2 of the grate-rest, and extending radially inward from said annular portion is a series of equally spaced apart grating portions 3.

Depended from the annular portion 2 of 45 the grate-rest 1 is a series of hook-shaped ledges 4, each of said hook shaped portions being for the support of a respective branch arm 5 of the grate hanger 6, said arms being extended from the centrally arranged hub 7 of said grate hanger 6, said hub being provided with a vertically extending bore 8.

For preventing each of the branch arms 5 from becoming disengaged from their

respective hooked-shaped portions 4, a stop 55 portion 9 is provided on each portion 4.

Arranged above the grate hanger 6 is a shaking spider 10, said spider having a centrally arranged cone shaped portion 11 which is provided with a plurality of inter- 60 stices 12 and extending radially from said centrally arranged portion 11 is a series of equally spaced apart closure portions 13.

The centrally arranged cone shaped portion 11 of the shaking spider 10 is provided 65 with a downwardly depending dowel or projection 14, said projection being depend- ed from the hub 15, which is arranged on the under side of said portion 11, said pro- 70 jection 14 being mounted within the bore 8 of the grate hanger 6, said hanger supporting said portion 11 in the manner described and in such supported position the closure portions 13 of the shaking spider 10, being 75 disposed horizontally on a plane beneath the base 16 of the cone shaped portion 11, will project on a plane beneath the grating portions 3 of the grate-rest 1.

Horizontally extending from the cone shaped portion 11 of the spider 10 is a series 80 of pushing or wiping fingers 17, there being the same number of fingers as there are closure portions 13, each finger being ar- ranged forwardly of a respective closure portion 13 and above a respective grating 85 portion 3 of the grate-rest 1 as shown in Figs. 1 and 3.

In assembling this improved grate the 90 grate-rest 1 is put in place above the ash pit, then the grate hanger 6 is located beneath the grate-rest and elevated to a position adjacent the under side of the grate-rest and the projecting arms 5 are each positioned adjacent a respective hook like portion 4 of the grate-rest and engaged onto 95 respective hooks.

The shaking spider 10 is then engaged to a lowered position above the grate-rest 1, proper care being taken so that each closure portion 13 of the shaking spider will be dis- 100 posed above a respective spacing 18 provided between each adjacent pair of grating por- tions 3 of the grate-rest as shown more clearly in Fig. 1, the centrally arranged pro- jection 14 of the spider 10 being engaged 105 within the bore 8 of the grate hanger 6.

One of the closure portions 13 is provided with a projecting portion 19, said project-

ing portion being disposed between a pair of depending lugs 20 which are formed integral with the under side of the annular portion 2 of the grate-rest 1, said projecting portion 19 and the pair of lugs 20 providing means for limiting the amount of oscillating movement to be given to the shaking spider 10.

Another of the closure portions 13 is provided with a projection 21 for the engagement of the socket portion of a shaking handle which is to be engaged over the projection 21.

In the operation of this improved grate when ashes accumulate thereon, the shaking handle is engaged over the projection 21 of the shaking spider 10 and when the handle is moved in a right hand direction the spider 10 will be horizontally turned upon the grate hanger 6 and as said spider is turned each closure portion 13 will be moved out or away from its closing position with respect to each respective space 18 thereby providing an opening between each adjacent pair of grating portions 3 of the grate-rest.

Owing to the pushing or wiping fingers 17 being also carried by the shaking spider 10, when the spider is moved and the closure portions 13 therewith, the pushing or wiping fingers 17 will also be moved and inasmuch as the fingers 17 are each respectively engaged above a respective grating portion 3 of the grate-rest 1, the accumulated ashes upon each grating portion 3 will be pushed off into an adjacent respective spacing or discharge opening 18.

The turning movement of the shaking spider 10 is stopped by engagement of the projection 19 with one of the limiting lugs 20 and in such stopped position the fingers 17 will be adjacent the opposite edge of their respective grating portions 3. The shaking spider 10 is moved in the opposite direction by rearward manipulation of the shaking handle in which the closure portions 13 will be returned to their neutral positions between respective adjacent pairs of grating portions 3.

In the event that clinkers and the like become lodged within the openings or spacings 18 when the closure portions 13 are disengaged from said openings, return movement of the shaking spider 10 will cause the closing portion 13 thereof which is adjacent the lodged clinker to wedge the clinker against an edge of the adjacent grating portion 3, such wedging movement against the clinker breaking it.

The cone shaped central portion 11 of the shaking spider 10 during the shaking movement will divert the downwardly moving ashes outwardly towards the openings 18 and the grating portions 3.

From an inspection of Fig. 4, it is to be noted that the pushing fingers 17 are ele-

vated a slight distance above the grating portions 3 so that they will not bear against said portions and cause friction.

What I claim is:—

1. A grate provided with a grate-rest, 70 said grate-rest having a plurality of discharging openings, closure means formed on said grate for each of said openings located on a plane below said openings, and a plurality of pushing elements borne by said 75 grate located on a plane above said openings movable with said closure means for co-operation with said openings.

2. A grate having a grate-rest, said grate-rest having a plurality of discharging openings, closure means formed on said grate for each of said openings located on a plane below said openings, supporting means for said grate, means depended from said grate-rest for upholding said supporting means, and a 80 plurality of pushing elements carried by said grate located on a plane above said openings of said grate-rest, said pushing elements being movable with said closure means for co-operation with said openings. 90

3. A grate provided with a grate-rest, said grate-rest having a plurality of discharge openings, a cone shaped shaking member arranged centrally of said grate-rest, means for supporting said member from said grate-rest, means borne by said member and arranged on a plane beneath said grate-rest for closing said openings of said grate-rest, and a plurality of pushing fingers borne by 95 said member each being so-operable with a 100 respective opening and arranged above said openings.

4. A grate provided with a grate-rest, said grate-rest having a plurality of inwardly disposed discharging spaces, a shaking member arranged centrally of said grate-rest and the spaces thereof, hook-shaped portions depended from said grate-rest, a hanger removably mounted on said hook-shaped portions for supporting said member, and means borne by said member arranged beneath said 105 grate-rest for closing the spaces of said grate-rest. 110

5. A grate provided with a grate-rest, said grate-rest having a plurality of discharge 115 openings, a shaking member arranged centrally of said grate-rest and the openings thereof, hook-shaped portions depended from said grate-rest, a hanger removably supported from said hook-shaped portions having an upwardly extending hub, said member having a centrally depended projection for engaging within the bore of the hub of said hanger, and a plurality of closing 120 portions borne by said member arranged beneath said grate-rest each being co-operative with a respective discharge opening of said grate-rest. 125

6. A grate provided with a grate-rest, said grate-rest having a plurality of discharge 130

openings, a shaking member arranged centrally of said grate-rest and the openings thereof, a hanger removably supported from said grate-rest having an upwardly extending hub, said member having a centrally depended projection for engaging within the bore of the hub of said hanger, a plurality of closing portions borne by said member arranged beneath said grate-rest each being co-operable with a respective discharge opening of said grate-rest, and a plurality of pushing fingers borne by said member each being co-operable with a respective discharge opening of said grate-rest and arranged above said opening.

7. A grate for a furnace or the like comprising a grate-rest, said grate-rest being in the form of a supporting ring and having a plurality of radially disposed spaces formed on its inner periphery, a shaking member supported from said ring having a plurality of radially disposed closure portions extended outwardly therefrom, said closure portions being depended so as to underengage said ring and respective discharging spaces thereof, and a plurality of pushing fingers borne by said member on a plane above said ring, each being arranged forwardly of a respective closure portion. 20 25

JOSEPH T. WILLARD.
